OR D 12,799

No. 12,799

MARCH 7, 1882

UNITED STATES PATENT OFFICE.

THOMAS J. HODGKINS, OF PEEKSKILL, NEW YORK, ASSIGNOR TO THE UNION STOVE WORKS, OF SAME PLACE.

DESIGN FOR A HEATING-STOVE.

SPECIFICATION forming part of Design No. 12,799, dated March 7, 1882.

Application filed January 16, 1882. Term of patent 7 years.

To all whom it may concern:

Be it known that I, THOMAS J. HODGKINS, of Peekskill, Westchester county, and State of New York, have invented a new and original Design for the Ornamentation of Heating-Stoves, of which the following is a specification.

My invention relates to the ornamental form and surface ornamentation of a heating-stove and its parts, as shown in the annexed engraving, forming a part of this specification; and, with the parts considered and described separately, it consists, first, in the form of the apex ornament A, which is placed on the stove-top, and has downwardly and outwardly tapering sides bounded by the scrolls $m' m'$, the intermediate angular top, m^2 , interior open-work, m^3 , and platform m^4 ; second, in the flattened pyramidal form of the stove-top proper, as indicated at O, and its exterior ornamentation, composed of the mitered and filleted moldings $O^2 O^3 O^4$, the intermediate open-work, $O^5 O^6$, and the overhang of the top O^7 ; third, in the manner of ornamenting the panels F F, one of which is placed at each of the upper corners of the stove-front beneath the overhang of the top, these panels having the grained surfaces e' , border e^2 , and an ornamental letter, e^3 , in relief in the panel-center; fourth, in the application of the elongated ornamental scroll-brackets E E, placed beneath the overhang of the top and upon the sides of the stove opposite the panels F F; fifth, in the application of the ornamental pilasters P P to the front of the stove, at the sides, with their molded and mitered caps beneath the overhang of the panels F F and their molded and mitered plinths on the stove-hearth, and their fronts longitudinally recessed, as indicated at p p; sixth, in the ornamentation of the stove-door upon the front, as indicated at D, consisting of the grained and recessed central panel, d' , with the trade-name of the stove displayed in relief letters therein, the filleted band-moldings $d^2 d^3$ upon the door-front, and the beveled band-molding d^4 upon the edge of the door; seventh, in the ornamentation of the end door,

S, consisting in the panel S², having the border-molding S³ and the grained surface S⁴, with a central oval ornament, S⁵; eighth, in the combination of the ornamental form and ornamentation of the apex ornament A, stove-top O, the panels F F, the ornamental brackets E E, pilasters P P, front stove-door, D, and that of end door, S, as I have detailed and described them 55 herein.

Having thus described my invention of a design and the sub-combination of the elements of which it is composed as applied to the parts of a stove, and in combination to its combined 60 parts, what I claim, and desire to secure by Letters Patent, is—

1. The design for the apex A, consisting of the downwardly-tapering side scrolls, $m' m'$, the intermediate angularly-pointed top, m^2 , interior open-work, m^3 , and the platform m^4 , as shown and described. 65

2. The design for the stove-top O, consisting of its flattened pyramidal form, its filleted and mitered moldings $O^2 O^3 O^4$, the intermediate 70 open-work, $O^5 O^6$, and the overhang of the top O^7 , as herein shown and described.

3. The design for stoves, consisting of the ornamental panels F F upon the stove-front, at the upper corners, beneath the overhanging 75 top, having grained panel-surfaces $e' e'$, molded border e^2 , and a letter, e^3 , in relief in the panel-center, as shown and described.

4. The design for stoves, consisting of the elongated brackets E E at the sides of the 80 stove-front and beneath the overhanging top, as shown and described.

5. The design for the ornamental pilasters P P, applied to the stove on the front, at the sides of the latter, with their mitered and 85 molded caps beneath the panels F F and their molded and mitered plinths on the stove-hearth, and having their fronts longitudinally recessed by means of the panels p p, as shown and described. 90

6. The design for the ornamentation of the front stove-door, D, consisting of the grained central recessed panel, d' , with the trade-name of the stove displayed therein in relief, the fil-

leted band-moldings d^2 d^3 upon the door-front, and the beveled band-molding d^4 upon the edge of the door, as shown and described.

7. The design for the end door, S, consisting of panel S^2 , having the grained surface S^4 and the central relief ornament, S^5 , as shown and described.

8. The design for the ornamentation of a heating-stove, consisting of the form and ornamentation of the apex A, stove-top O, the pan-

els F F, ornamental brackets E E, pilasters P P, front stove-door, D, and end door, S, as shown and described.

Signed at Peekskill this 22d day of December, 1881.

THOMAS J. HODGKINS.
